F. FRASER

SHEET GLASS EDGE FORMING MEANS

Original Filed June 5, 1925

INVENTOR.

Frank Fraser.

UNITED STATES PATENT OFFICE.

FRANK FRASER, OF TOLEDO, OHIO, ASSIGNOR TO THE LIBBEY-OWENS SHEET GLASS COMPANY, OF TOLEDO, OHIO, A CORPORATION OF OHIO.

SHEET-GLASS-EDGE-FORMING MEANS.

Application filed June 5, 1925, Serial No. 35,062. Renewed September 26, 1927.

The present invention relates to sheet glass apparatus, and has particular reference to sheet edge forming means.

An important object of the invention is to provide sheet glass apparatus for producing flat sheet glass, and includes means arranged at both edges of the sheet adapted to engage and form a suitable edge on the sheet capable of overcoming the natural tendency of the sheet to narrow.

Another object of the invention is to provide stationary edge means for gripping the edges of the sheet at their bases and movable means above the stationary means to further assist in maintaining the sheet to width.

Still another object of the invention is to provide at each edge of the sheet being drawn from a mass of molten glass a stationary block member having a slot therein through which the edge of the sheet is drawn and rotatable rolls above the slot for assisting the block means in creating an edge on the sheet, the said rolls being adapted to either retard or advance the edge glass.

Other objects and advantages of the invention will become apparent during the course of the following description.

In the drawings wherein like numerals are employed to designate like parts throughout the same,

Fig. 1 is a fragmentary transverse vertical section through a sheet glass apparatus illustrating my improved device in operation,

Fig. 2 is an end view thereof,

Fig. 3 is a top plan, and

Fig. 4 is a perspective view.

This device is particularly well-adapted for use in the Colburn type of machine as set forth in Patent No. 1,248,809, granted December 4, 1917, although it is not necessarily limited to the Colburn machine as it can be used in any type of machine wherein a flat sheet of glass is drawn from a source of molten glass.

The numeral 5 designates a so-called drawing pot containing a mass of molten glass 6, from which a sheet 7 is drawn from the sheet source 8. A bending member 9 may be provided to deflect the sheet from one plane to another.

In the Colburn machine a pair of rotatable knurled rolls are positioned at both edges of the sheet being drawn at the meniscus thereof

to form a so-called knurled edge on the sheet to hold the same to width. The natural tendency of a sheet of glass being drawn from a mass is to narrow at its base and draw to a thread. One of the great difficulties in the production of sheet glass is to prevent this natural tendency of the glass to narrow without spoiling the quality of sheet formed.

Although the knurled rolls used in the Colburn process are entirely satisfactory, they form what is known as a knurled edge on the sheet and a thickened portion which extends about six or seven inches from the edges toward the center, which edges must be removed when the sheet is being cut up into commercial sizes. The net width of sheet is therefore considerably less than the gross width.

It is an aim of the present invention to provide means capable of holding the sheet to width, at least as satisfactorily as the knurled rolls now used, and which will also hold the sheet to width without creating such a large useless portion.

The numeral 10 designates what may be called a slotted block. The slot is indicated as at 11. The block may be formed from a refractory material such as clay, or as shown in the drawings may be formed from a preferably non-corrosive metal which may be internally cooled as through the conduits 12. Thus the blocks may be formed with an internal bore having connection with the conduits 12, whereby a cooling medium such as air or water may be continuously circulated through the said block. The block may assume any number of shapes, and as shown in Fig. 2 comprise a pair of foot portions 13 which are adapted to be partially submerged in the bath of molten glass from which the sheet is drawn. As shown in Fig. 4 the slot is continued up the sheet for a comparatively high distance by making the neck 14 comparatively taller than the neck 15 in Fig. 2.

The blocks may be carried on the arms 16 which are supported in any suitable manner. The slotted members have a dual function in that they create a positive frictional resistance to the glass passing into the border portions of the sheet, and they also absorb sufficient heat from this glass to create a relatively viscous edge capable of overcoming the natural tendency of the sheet to narrow. The

glass will drag along the bottom of the shoes 13 because of the natural tendency of molten glass to adhere to such bodies.

The slot 11 may be enlarged at its end as 5 at 17 to form what is known as a beaded edge 18.

In addition to the slotted block just described, I provide preferably smooth rotatable rolls 19. One roll is arranged on each 10 side of the edge of the sheet as is clearly indicated in Fig. 4 directly above the slot 11, thus forming a continuation thereof. The rolls are supported upon the rotatable shafts 20 which may be internally cooled and are 15 supported and driven through the mechanism 21. A changeable speed drive is desirable so that the speed of rotation of the rolls can be controlled. The rolls 19 may either be rotated faster than the speed of draw if it 20 is found that the blocks are offering too much resistance, or if the blocks have not sufficient resistance, the rolls may be rotated relatively 25 slower than the speed of draw. Of course the rate of rotation of the rolls and the speed of draw can be identical if desired.

With the smooth rolls which may be provided with a groove 22 to accommodate the beaded edge 18, the sheet will be held to width while at the same time the comparatively 30 large knurled edge formed on the sheet heretofore will not be in evidence. The combination of the frictional resistance of the block, as well as the heat absorption and the rotatable rolls, a decidedly improved edge will be 35 formed on the sheet. The edges thus formed can be trimmed off and used for shelving purposes, etc., while the remainder of the sheet can be handled as heretofore.

Claims:

- 40 1. In sheet glass apparatus, means for drawing a sheet from a mass of molten glass, stationary means arranged at the base of the sheet at its edges for retarding the movement of the glass entering the sheet edges, and rotatable means arranged above the said stationary means and closely adjacent thereto.
2. In sheet glass apparatus, means for drawing a sheet from a mass of molten glass, slotted stationary means arranged at the base 50 of the sheet and at its edges for retarding movement of the glass thereto, and rolls arranged above said slotted member and closely adjacent thereto.
3. In sheet glass apparatus, means for drawing a sheet from a mass of molten glass, stationary slotted means arranged at the base 55 of the sheet for retarding movement of glass to the border portions thereof, and a pair of rolls above each of the slotted means.
- 60 4. In sheet glass apparatus, means for drawing a sheet from a mass of molten glass, stationary slotted means arranged at the base of the sheet at its border portions thereof, and

a pair of rotatable rolls above each slotted member adapted to engage the edge of the 65 sheet after it emerges from the said slot.

5. In sheet glass apparatus, means for drawing a sheet from a mass of molten glass, a slotted block arranged at the base of the sheet and one at each edge thereof, a portion 70 of each of the blocks being disposed below the end of the glass from which the sheet is drawn, and a pair of rotatable rolls arranged above the slot in each block.

6. In glass drawing apparatus employing 75 a source of molten glass from which a sheet is to be drawn, means partially submerged in the source of glass for engagement with both sides of the edge portions of the sheet being drawn to create a dragging action for 80 retarding movement of the sheet at its border portions, and rotatable means arranged above the said stationary means and closely adjacent thereto.

7. In glass drawing apparatus, employing 85 a source of molten glass from which a sheet of glass is to be drawn, means at the edges of the sheet for holding the same to width, comprising a body portion and a plurality of lip 90 portions extending therefrom and terminating below the level of the molten glass from which the sheet is drawn, and rotatable means arranged above the stationary means and closely adjacent thereto.

8. In glass drawing apparatus employing 95 a source of molten glass from which a sheet is to be drawn, a block having spaced lip portions thereon forming a slot through which the sheet being drawn passes for retarding the movement of the border portions thereof, and 100 a pair of rolls arranged above the slotted block for engagement with the sheet.

9. In glass drawing apparatus employing 105 a source of molten glass from which a sheet is to be drawn, a block having spaced lip portions thereon forming a slot through which the sheet being drawn passes for retarding the movement of the border portions thereof, a pair of rolls arranged above the slotted block 110 for engagement with the sheet, and means for controlling the temperature of said slotted block.

10. In glass drawing apparatus employing 115 a source of molten glass from which a sheet is to be drawn, a block having spaced lip portions thereon forming a slot through which the sheet being drawn passes for retarding the movement of the border portions thereof, a pair of rolls arranged above the slotted block 120 for engagement with the sheet, and means for controlling the temperature of the slotted block and rolls.

Signed at Toledo, in the county of Lucas, and State of Ohio, this 3rd day of June, 1925.

FRANK FRASER.
